ARRANGEMENT FOR HEATING GASES
FLOWING THROUGH SHAFTSLennart Högel, Västerås, Sweden, assignor to All-
männa Svenska Elektriska Aktiebolaget, Vas-
terås, Sweden, a corporation of SwedenApplication June 7, 1933, Serial No. 674,645
In Sweden June 10, 1932

7 Claims. (Cl. 219—39)

For heating gases flowing through shafts to very high temperatures, generally for the purpose of accomplishing chemical processes such as carbureting carbon dioxide, hitherto only 5 electrical arcs have been practically applied. The heating of gases by means of electrical arcs is, however, a very costly method in comparison with heating by means of electrical resistances, but this latter method involves very great difficulties as the heating temperature of the gas for 10 certain processes lies at about 1100° or 1200° C., when the molecular strength of the resistance material begins to weaken. It has been proposed to arrange the resistance elements on shelves 15 in the shaft in order to avoid the deformation of the material, but this means has the disadvantage that the flow of the gas in close proximity of the element is obstructed and therefore the transfer of heat will be less satisfactory.

The present invention refers to an arrangement by means of which the heating of gases flowing through a shaft is effected by means of freely hanging electrical resistance elements round which the gas is flowing without obstruction. The heating then can be driven almost up 20 to such a temperature that the material is stressed to its yield point under its own weight. The elements are composed by commercially obtainable resistance material, preferably consisting of metal or metal alloys of which of course 25 the types most heat resisting and most insensitive to the chemical influences of the gas should be chosen. Nickel-chromium-iron alloys have proved to be particularly suitable especially in carbureting carbon dioxide, when the oxidizing effect of the gas or gas mixture is very feeble at the temperatures in question.

In the accompanying drawing two forms of arrangements of the invention are illustrated.

40 Fig. 1 is a transversal sectional view of a circular shaft with a three-phase arrangement of the electrical resistance and Fig. 2 shows a longitudinal sectional view of the same with three such resistances.

45 Fig. 3 is a transversal sectional view of a square shaft with a resistance for direct current or single phase current and Fig. 4 shows this shaft in a longitudinal sectional view also with three resistances.

50 In all the figures, 1 designates the shaft and 2 the electrical resistances which consist of resistance elements 3 such as rods, bars or the like fixed to an upper part 4 attached to the inner circumference of the shaft, and a lower freely 55 hanging part 5, embodying a certain weight.

This means enables the resistance elements to expand in the longitudinal direction of the shaft retaining their position relative to each other, and the heating may therefore be driven as high as the tenaciousness of the material permits. 5

In Figures 1 and 2 an arrangement is shown in which the upper part 4 is arranged round the whole inner circumference of a circular shaft and the resistance elements 3 are joined in a point in the part 5, which may be cylindrical, 10 as the drawing shows, or shaped as a cone, a ring or the like.

The arrangement shown in Figures 1 and 2 may be used not only with circular, but also with any other sectional form of the shaft. In square 15 shafts the arrangement shown in Figures 3 and 4 may be used advantageously. Here the upper part consists of two rods 4, attached to opposite sides of the shaft, and the resistance elements 3 are placed in two planes, which are joined in 20 the form of a V at the lower rod shaped part 5.

The resistances are hung at suitable distance above each other. The drawing only shows three resistances, but the number must of course be adapted in accordance with the heating requirements. 25

By dividing the upper part 4 into two or more parts each with the same number of resistance elements and each part provided with a terminal 6, the resistances may be used for different kinds 30 of current. By dividing it into two parts the resistance will be suitable for single phase or direct current. This dividing makes it possible to connect several units in series or in delta or star for use with three phase current. By dividing the 35 resistance into three parts each resistance may be directly connected to a three-phase system, whereby the lower part 5 forms the neutral point of the system.

The resistance elements are shown in the 40 drawing as bars of rectangular section. In this form the elements should preferably be oblique, for instance as the wings of a fan, in order to bring the flow of gas into closer contact with the resistance elements. The arrangement would 45 especially in round shafts cause a rotating or whirling movement along the central line of the shaft. In order to avoid this very undesirable movement, the elements of each resistance may be inclined in the opposite direction to the elements of the next preceding one. The elements of each particular resistance may also be inclined in different directions for the same purpose. By inclining the elements in different directions a more intimate mixing of the different 50 55

constituents of the gas is obtained which will advantageously influence the chemical process.

I claim as my invention:

- 5 1. Electric heating means for gases comprising a shaft adapted to be traversed by a gas current and strongly inclined grid-like metal resistance elements comprising downwardly converging bars substantially covering the cross-sectional area of said shaft and extending to the center line thereof.
- 10 2. Electric heating means for gases comprising a shaft adapted to be traversed by a gas current and inclined resistance bars suspended in said shaft and converging downwardly to form a grid-like structure substantially V-shaped in vertical section, said bars having rectangular cross-section with the largest dimension substantially parallel or slightly inclined to the longitudinal direction of said shaft substantially covering the cross-sectional area of the shaft.
- 15 3. Electric heating means for gases comprising a shaft adapted to be traversed by a gas current and heating resistance bars suspended from the walls of said shaft and forming a grid-like structure, substantially V-shaped in vertical section.
- 20 4. Electric heating means for gases comprising a shaft of substantially circular cross-section adapted to be traversed by a gas current, and heating resistance bars each suspended from the

peripheral wall of said shaft and all converging downwards and connected together at their lower ends at the axis of the shaft.

- 5 5. Electric heating means for gases comprising a shaft adapted to be traversed by a gas current, and a plurality of groups of heating resistance bars each group being independently suspended from the walls of said shaft and all said bars converging downwards to form several grid-like structures, one above the other and each 10 substantially covering the cross-sectional area of the shaft.

- 10 6. Electric heating means for gases comprising a shaft adapted to be traversed by a gas current, and several groups of resistance bars arranged 15 one above the other and converging from the sides towards the centre of the shaft, a heavy body holding together the lower ends of the bars in each group, said bars being of rectangular cross-section, the largest dimension of which is 20 slightly inclined to the longitudinal direction of the shaft alternatively in either direction.

- 15 7. Electric heating means for gases, comprising a shaft adapted to be traversed by a gas current, heating resistance bars suspended from 25 the walls of said shaft and converging downwards, and a heavy body holding together the lower ends of said bars.

LENNART HÖGEL.
